UNITED STATES PATENT OFFICE.

EDWARD C. MCKENZIE-MARTYN, OF SHORT HILLS, NEW JERSEY, ASSIGNOR TO STAND-
ARD DEVELOPMENT COMPANY, OF NEW YORK, N. Y., A CORPORATION OF DELA-
WARE.

VAPORIZER-CONTROL DEVICE.

Application filed December 22, 1922. Serial No. 608,468.

This invention relates to vaporizer control devices, and will be fully understood from the following description reference being had also to the accompanying drawing 5 which represents a central sectional view of a form of apparatus contemplated.

While the invention is applicable in various usages, it will be described for illustration as applied to the feeding of knock-controlling agents to internal combustion engines, and in the drawing the reference character 1 designates the air intake leading to a carburetor C of any desired form; the usual choker valve 3 and throttle valve 3' being provided. Extending into the air passage is a tube 4 with a perforated wick-cage 5 carrying a wick 6 which projects below into a liquid container 7. Advantageously such container is attached to the tube 4 by a screw-thread joint or the like, so as to be readily detachable, such container supplying in convenient manner a chemical agent efficient in modifying the combustion of hydrocarbon fuels to the end of checking knocking or detonation. Slidable over the wick-cage 5 is a cover or closure 8 which is attached to a diaphragm 9 whose other surface is exposed to the chamber 10 which is in communication through the pipe 11 with the intake manifold. Closing the other side of the chamber 10 is a diaphragm 12 whose inner surface carries a projection 13 which slides within a cylindrical projection 14 attached to the diaphragm 9, a duct 15 through the projection 13 communicating with chamber 10. The diaphragm 12 is pulled upon externally by a tension spring 16 which is adjustable by means of a thumb-screw 17 threaded in a sleeve 18 which in turn is 40 threaded in a support 19. The sleeve 18 serves as an adjustable back-stop for the diaphragm 12. Suitable lock means, such for example as the spring dogs 20 engaging the milled edges of the screw 17 and sleeve 18 are provided to hold these elements in the positions for which set. A light spring 21 between the diaphragm 9 and abutment 2 may be provided to insure holding the cover 8 properly seated when the device is not in 45 operation. The tube 4 being screw-threaded allows of adjustment of its position with respect to the closure 8, and a lock-nut 23 serves to maintain it in adjusted position.

When the engine is at rest, the pressure in the intake manifold as communicated

through pipe 11 to the sides of the diaphragms exposed in chamber 10 is not different from the pressure effective upon their other sides and correspondingly the spring 21 is operative unopposedly to hold the closure 8 over the wick-cage and thus prevent evaporative waste of the knock-controlling agent. When the engine is running the pressure from the intake manifold through pipe 11 to the sides of the diaphragms exposed in chamber 10 is less than that effective upon their other sides and the diaphragm 9 is elevated so as to raise the closure 8 and allow the chemical agent supplied by the wick to be volatilized from its moist surface and carried to the engine cylinders with the fuel mixture provided by the carburetor. The amount of the chemical agent or knock controller so supplied is sufficient to check knocking. During this time the diaphragm 12 is restrained in position by the tension spring 16; but when the engine speed runs up to a point beyond that for which the spring 16 has been set, the pressure in the intake manifold and in the chamber 10 is reduced such that the diaphragm 12 is depressed, carrying down with it the projection 13 to such extent as in its extreme position to force down the diaphragm 9 and closure 8, thus cutting off the knock-controlling agent when engine conditions are such as not to require it. The diaphragm 12 may be of larger area than the diaphragm 9 in order to get this differential action of the outer diaphragm over the inner diaphragm, or irrespective of the sizes of the diaphragms, the differential action may be secured by spring adjustment.

Changes may be made, within the spirit and scope of the invention, it being understood that the invention is to be regarded as limited only as defined in the following claims, in which it is my intention to claim all inherent novelty as broadly as the prior art permits.

What I claim is—

1. The combination with an air intake and manifold and carburetor of an internal combustion engine, of a wick tube and a wick cage projecting into the air intake, a wick in said tube and cage, a container for liquid detachably connected to the lower end of the wick tube, a closure slidable over the wick cage, a pressure-responsive diaphragm

connected to said closure, a spring normally tending to hold said closure in its closed position, a second pressure-responsive diaphragm, a projection from said second diaphragm operative to approach and ultimately move the first mentioned diaphragm, a spring normally restraining the second diaphragm in a direction away from the first mentioned diaphragm, an adjustable 5 back-stop for the said second diaphragm, and means for communicating the pressure effective in the intake manifold to the opposing surfaces of the two diaphragms.

2. The combination with an air intake and 15 manifold and carburetor of an internal combustion engine, of a wick projecting into the air intake, means for supplying a liquid to said wick, a closure slidable over the wick, a pressure responsive diaphragm connected 20 to said closure, a second pressure-responsive diaphragm, a projection from said second diaphragm operative to approach and ultimately move the first mentioned diaphragm, a spring normally restraining the second 25 diaphragm in a direction away from the first mentioned diaphragm, an adjustable back-stop for the said second diaphragm, and means for communicating the pressure effective in the intake manifold to the opposing 30 surfaces of the two diaphragms.

3. The combination with an air intake and manifold and carburetor of an internal combustion engine, of a source of vapor opening into the air intake, a closure movable over 35 said vapor source, a pressure-responsive diaphragm connected to said closure, a second pressure-responsive diaphragm having a projection operative to approach and ultimately move the first mentioned diaphragm, a 40 spring normally restraining the second diaphragm in a direction away from the first mentioned diaphragm, and means for communicating the pressure effective in the intake manifold to the opposing surfaces of the two diaphragms.

4. The combination with means for supplying a combustion mixture to an internal combustion engine, of opposed, independently movable diaphragms actuated by pressure 50 differentials prevailing in the intake conduit of the engine, a source of knock-controlling agent, and means actuated by said diaphragms for governing the feed of such agent.

5. The combination of a source of vapor, a closure movable over said vapor source, a pressure-responsive diaphragm connected to said closure, a second pressure-responsive diaphragm having a projection operative to 55 approach and ultimately move the first mentioned diaphragm, means for normally restraining the second diaphragm in a direction away from the first mentioned diaphragm, and means for communicating the

pressure effective in the intake manifold of 65 an internal combustion engine to the opposing surfaces of the two diaphragms.

6. The combination of an opening for fluid supply, a closure movable over said opening, a pressure-responsive diaphragm 70 connected to said closure, a second pressure responsive diaphragm having a projection operative to approach and ultimately move the first mentioned diaphragm, and means for communicating the pressure effective in 75 the intake manifold of an internal combustion engine to the opposing surfaces of the two diaphragms.

7. The combination of an opening for fluid supply, a closure movable over said 80 opening, a pressure-responsive diaphragm connected to said closure, and a second pressure-responsive diaphragm operative to approach and ultimately move the first mentioned diaphragm.

8. Means for supplying material to the intake manifold of an internal combustion engine, said means comprising a source of supply, a closure therefor, diaphragm mechanism normally spring-pressed to seat said 90 closure, means for communicating the pressure in the intake manifold to said diaphragm whereby upon a predetermined reduction of pressure the diaphragm moves the closure from its seat, and a second diaphragm mechanism mounted independently of the first and operable upon a predetermined further reduction of pressure to return the closure to its seat.

9. In means for supplying a knock-controlling agent to the intake manifold of an internal combustion engine, the combination of a source of a knock-controlling agent, a closure therefor, opposed diaphragm regulating the position of said closure, a pipe 100 connecting the intake manifold with the space between the diaphragms, and spring means adapted to control the position of the diaphragms until predetermined pressure conditions are reached.

10. In means for supplying a knock-controlling agent to the intake manifold of an internal combustion engine, the combination of a source of a knock-controlling agent, a chamber comprising opposed diaphragms, a closure for said source carried by one of said diaphragms, a pipe connecting the chamber with the intake manifold whereby upon reduction of pressure in the latter said diaphragm removes the closure, means normally sustaining the second diaphragm, and an extension upon said second diaphragm adapted to engage the closure-carrying diaphragm and to depress the same when a predetermined reduction of pressure is produced in the chamber.

EDWARD C. MCKENZIE-MARTYN.
